UNITED STATES PATENT OFFICE.

MANASSAH GLEDHILL, OF OPENSHAW, ENGLAND, ASSIGNOR TO THE SIR JOSEPH WHITWORTH & COMPANY, LIMITED, OF SAME PLACE.

ORDNANCE.

SPECIFICATION forming part of Letters Patent No. 566,679, dated August 25, 1896.

Application filed July 21, 1892. Renewed July 31, 1896. Serial No. 601,205. (No model.)

To all whom it may concern:

Be it known that I, MANASSAH GLEDHILL, director of the Sir Joseph Whitworth & Company, Limited, of Openshaw, Manchester, 5 England, engineers, a subject of the Queen of Great Britain, and a resident of Openshaw, Manchester, England, have invented certain new and useful Improvements in and Relating to the Manufacture of Ordnance, (for 10 which I have obtained a patent in Great Britain, No. 9,561, dated July 6, 1887,) of which the following is a specification, reference being had to the accompanying drawings.

My invention relates to the manufacture of 15 ordnance and comprises various improvements, as hereinafter described, in and relating to guns of that class wherein steel tubes, hoops, or rings are placed one upon another in such a manner that together they complete 20 the structure of the body of the gun.

The said invention has for its chief object 25 the construction of a gun by building up a series of tubes, hoops, or rings so formed, fitted together, and united as to insure great 30 strength and durability of the gun while permitting the ready withdrawal or removal of the liner and the insertion of a new liner without injury to or displacement of the other tubes or hoops; and the said invention comprises 35 a novel manner of providing for the fitting together of the said tubes or hoops with great accuracy and with a determined allowance for endwise adjustment, or for shrinkage, so that the proper relative position 40 of the parts involved in the structure of the gun can be insured and permanently maintained.

In the accompanying drawings, Figure 1 is 45 a longitudinal central section of a gun constructed according to my said invention. Fig. 1^a shows a portion of Fig. 1, drawn to an enlarged scale. Fig. 2 shows another portion of Fig. 1, also drawn to an enlarged scale. Fig. 3 is a rear or breech end view of the said 50 gun, also drawn to an enlarged scale. Fig. 4 is partly a side elevation and partly a longitudinal central section, and Fig. 5 is a similar view, both drawn to an enlarged scale, showing locking-rings, hereinafter described. Fig. 50 6 is partly a side elevation and partly a longitudinal central section of another gun, illus-

trating a modification of my said invention. Fig. 7 shows a portion of Fig. 6 drawn to an enlarged scale. Figs. 8, 9, and 10 are longitudinal central sections illustrating other 55 modifications of my said invention. Fig. 11 is a rear or breech end view of a gun, illustrating a modification. Fig. 12 is a longitudinal section illustrating a modified form of breech-plug ring, and Fig. 13 is a similar 60 view showing a modified form of liner. Fig. 14 is a detail perspective view of one of the wedges *g*.

Like letters indicate corresponding parts 65 throughout the drawings.

The tubes A, B, and hoop C of the gun are respectively indicated by these letters.

a is the liner or inner lining of the gun.

One important feature of my said invention is the employment of peculiarly constructed 70 locking-rings *b b'* between the tubes A B and hoop C at the breech end of the gun, as follows, that is to say, at the breech end of the gun, between the tubes A and B and between the tube B and hoop C, I form a cavity 75 or recess the walls of which will be the surfaces of the tubes, as shown in Figs. 1, 2, and 3. On each of these surfaces I cut a screw-thread, and into the cavity thus formed I insert one of the said locking-rings, which is 80 screw-threaded on its inner and outer surfaces, as shown in Fig. 4 or in Fig. 5, to fit the threads in the cavity or recess, into which the said ring is tightly screwed. In some instances I form segmental or interrupted 85 screw-threads *j* on the ring and on the surfaces of the tubes or hoops in the said recess or cavity, as shown in Fig. 11, these segmental threads being so arranged that those on the ring will pass endwise between those in 90 the recess, so that the ring may be freely inserted and then turned far enough round to cause the threads thereon to engage with those of the recess. By these means I secure the tubes or hoops firmly and solidly 95 together at the breech end of the gun. In some instances I split or divide these rings and secure them in place with keys or wedges *g*, Fig. 3, so that they can be readily removed, as hereinafter described with reference to 100 the breech-plug ring.

The tubes or hoops of which the gun is

composed are preferably made in one piece and are continuously and uniformly tapered throughout their length, so that the required diminution in the external diameter of the gun from the breech to the muzzle is obtained without shoulders or sudden changes of thickness, which are very prejudicial to the strength of the tubes. The continuous taper of the liner *a* greatly facilitates its removal and replacement. Moreover, by the employment of the said continuously and uniformly tapered tubes I can adopt a method of manufacture wherein I avoid the necessity for the use of gages in fitting the various tubes one upon another, that is to say, I turn or otherwise form the outside of one tube and bore out the other tube so that both tubes are continuously tapered at the same angle from end to end and the external diameter of the one is so nearly the same as the internal diameter of the other that the outer tube can be placed very nearly in its ultimate position upon the inner tube without any or with but very slight pressure; then, the remaining distance and the angle being known, it is easy to ascertain the exact pressure to which the tubes will be subjected in forcing the one to its ultimate position upon the other.

The liner *a* may be forced home by applying to it hydraulic or other pressure as great in amount as or greater than the total pressure exerted by the powder-gases in the chamber of the gun. The tubes *A*, *B* and hoop *C* may be put together by hydraulic pressure or with shrinkage.

If the outer tube is to be shrunk upon the inner tube, I know, or can ascertain, the exact amount to allow for shrinkage. Moreover, the continuously taper formation of the said tubes greatly facilitates the uniform shrinking of one upon the other, a much lower temperature being required and the danger of injuring the tubes for hoops being much less than in the case of parallel tubes. The latter, unless the contraction of the outer tube is exactly equal or uniform at all parts, will be liable to have one end or part bind or become tight, while the other part or parts, still being free, as the tube continues to shrink will be drawn against very great frictional resistance toward the fixed end or part, thereby injuriously straining the metal; but with taper-tubes this difficulty will not exist or will be considerably diminished.

When the tubes or hoops are to be put together with shrinkage, I prefer that they should be heated to a temperature not exceeding three hundred degrees (300°) Fahrenheit.

To facilitate the formation of the taper-tubes and the accurate fitting of the one upon the other as above described, I employ a mandrel which, in respect of its diameter and taper formation, is a counterpart or facsimile of the inner one of the aforesaid tubes. The outer tube is so fitted to this mandrel that when removed therefrom and placed upon the inner tube it can be placed thereon with

very little pressure within a short distance of its ultimate position and can then be forced home with or without shrinkage, as above described. This method of first accurately fitting the taper-tubes to each other within a short distance of their proper relative positions and then forcing one tube home or expanding and shrinking it upon the other enables me to secure the liner in the gun in such a manner that, although it will not be liable to accidental displacement, it can be readily withdrawn when worn without injury to or displacement of the other tubes or hoops of which the gun is built up.

As an alternative to the use of a tube made in one piece continuously taper from end to end, I, in some instances, make the inner tube, that is to say, the *A* tube, containing the liner, or the *B* tube, or other intermediate tube or tubes, in two or more continuously taper pieces or lengths, united by screwing the said pieces together, the screw-joints being made taper, with a plain or unscrewed portion at the end of each hoop to insure the proper fitting of the parts together, as shown in Fig. 1 or Fig. 1^a. It is obvious that this form of joint, for the purpose herein specified, is stronger and more reliable than an ordinary rabbeted or square-shouldered joint, and it considerably facilitates the connection and disconnection of the parts.

I sometimes coil wire around the liner *a*, as shown at *c* in Figs. 6 and 7, so that when the said liner is in its place there will be a space between it and the *A* tube surrounding it occupied by this wire, which will afford a strong and elastic support to the liner, so that it can withstand the stresses due to the firing of the gun without being so tightly forced into the *A* tube as to make its withdrawal therefrom a very difficult operation.

On the breech end of the liner *a* I cut a screw-thread, whereon I fit a nut *d*, which I term the "liner-nut." In the gun shown in Figs. 1, 2, and 3 I form for the reception of this nut a recess or cavity in the end of the *A* tube, as shown at *e* in Figs. 1 and 2. Instead of the nut I sometimes form on the liner a solid collar *a'*, which will enter the said recess or cavity, as shown in Fig. 13.

The nut *d* can be screwed upon the liner before the latter is forced home in the *A* tube, and affords the means for insuring or assisting to insure the accurate adjustment of the liner to its exact position within the tube and prevents injury to the latter by forcing the liner too far into the said tube, that is to say, the nut *d* or the solid collar, being in close contact with the bottom or end of the recess or cavity in the *A* tube, will limit the endwise movement or adjustment of the liner, so that in applying the pressure for forcing the liner into the said tube no other precaution in respect of insuring its true position therein or preventing injury to the *A* tube will be necessary except to ascertain that the nut or collar is properly home against

the end of the recess in the said tube. Moreover, I can thus avoid all danger arising from too great contraction of the said tube in shrinking it upon the liner. The said nut *d*, 5 moreover, protects the screw-thread at the rear end of the liner, and can be readily unscrewed to permit the application of a device for removing the said liner.

I may make the rear end of the liner *a* 10 slightly enlarged and screw-thread this portion, as shown in Fig. 12, and recess the inner end of the breech-plug ring and screw-thread the same in such manner as to engage the corresponding screw-thread formed upon the 15 rear end of the liner *a*.

In the gun shown in Fig. 8, a single locking-ring *b* is screwed into a recess or cavity formed between the tube *A* and the hoop *C* by shortening the tube *B*. The tubes *A* *B* 20 are in this instance formed with shoulders *A'* *B'*, which, when the said tubes are in their proper relative position, abut against each other, as shown.

The *A* tube at its rear end has provision 25 for the reception of the breech-plug ring *f*, which is screwed into the said end of the tube and is so arranged that its inner end bears upon the rear face of the liner *a* and liner-nut *d*. The breech-plug ring *f* has the usual segments or interrupted screw-threads to engage with similar threads on the breech-plug. I sometimes split or divide the breech-plug ring on one side and drive one or more wedges or keys *g* into the aperture, as shown in Fig. 30 35 to tighten the ring in its place. By this device I greatly facilitate the removal of the said ring, that is to say, instead of having to exert sufficient force to unscrew the said ring while its screw-threads are tightly engaged 40 with those of the tube, I can draw out the wedge or key *g*, and thereby slacken the ring *f* within the *A* tube, so that the said ring can be very easily unscrewed. I provide suitable means for securing the wedge or key *g* in 45 place and for turning the said ring in screwing it into or out of the tube. As a modification of the above, I sometimes make the breech-plug ring in two or more parts or segments, which I secure in place by keys or 50 wedges driven in and secured as above described.

The breech-plug is usually cylindrical, but I sometimes make it taper, as shown, for example, in Figs. 9 and 10, either with segments or continuous screw-threads, to facilitate the opening and closing of the breech.

In some instances I use a hoop screw-threaded internally, as shown at *i*, Figs. 1 and 6, for securing together the adjacent ends of 60 the hoop *C* and tube or hoop *B*, or of other other tubes or hoops.

In the gun shown in Fig. 9 the liner *a* is 65 enlarged at its rear or breech end and a locking-ring *b* is screwed into a recess between the said liner and the tube or hoop *B*. The liner *a* is formed with a curved shoulder *a'*, and the tube *A* is correspondingly curved at

A'. The breech-plug *h* is made taper with a continuous screw-thread, and is fitted into the breech end of the liner *a*, which is formed 70 with a corresponding internal screw-thread.

I sometimes provide for facilitating the removal or withdrawal of the locking-ring by making the same in two parts *b*² *b*³, as shown in Fig. 10. The part *b*² is made with an internal screw-thread and is to be inserted before the part *b*³. The latter is made with an external screw-thread, and both parts are formed with shoulders, which abut against each other, as shown. The ring *b*³ is a slack 80 fit on the ring *b*², and can therefore be readily unscrewed from the tube or hoop *B*. The ring *b*³ can then be unscrewed from the liner *a*, which may then be withdrawn. The rings *b*² *b*³ in this case do not require to be split or 85 divided.

One important advantage arising from my improved construction is that I can make the parts interchangeable, so that if any part of a gun is injured or destroyed it can be 90 readily replaced or renewed. Moreover, the said invention affords the means for so constructing the gun that its various parts can be properly fitted together and then taken asunder and very conveniently packed for 95 transport to any distant station, where they can with very simple appliances be again put together. I thus provide for supplying heavy guns with very little delay to any place where siege or other military operations may 100 be proceeding, or to ships in foreign or colonial stations, or to other places where such guns may be required.

I wish it understood that I do not limit myself in the construction of my improved 105 guns to any particular number or thickness of the tubes, nor do I claim generally or otherwise than as means for effecting the object of my improvements as herein set forth the taper formation of the tubes or liners used 110 in built-up guns nor the making of a liner of one continuous taper from end to end, nor do I claim otherwise than when constructed and applied as herein specified the use of screw-threaded rings at the breech end of such 115 guns for securing the tubes or hoops together; but—

I claim—

1. In a built-up gun, the combination with the concentric tubes locked together, the inner one of which is provided at its rear end with an internally-threaded cylindrical recess or chamber, of the continuously and uniformly tapered liner *a* provided at its rear end with an annular enlargement adapted to 120 seat within said recess or chamber, and a threaded breech-plug ring screwed into said recess or chamber and operating to hold the liner in position, substantially as described.

2. In a built-up gun, the combination with 130 a plurality of concentric tubes externally screw-threaded and provided with internally-threaded recesses at their breech ends, of locking-rings screw-threaded internally and

externally and screwed into said recesses, substantially as described.

3. In a built-up gun, the combination with a plurality of concentric tubes recessed and screw-threaded internally and externally, of locking-rings formed of a plurality of segmental sections fitted in said recesses, and wedges inserted between the ends of said segmental sections, substantially as described.

4. In a built-up gun, the combination with a plurality of concentric tubes screw-threaded internally at their breech ends, of a locking-ring formed in two concentric parts screw-threaded upon their opposite peripheries and correspondingly shouldered upon their adja-

cent peripheries and fitted between the breech ends of said tubes, substantially as described.

5. In a built-up gun, the combination with a plurality of concentric tubes, of a liner *a*, and a breech-plug ring split or divided longitudinally, and a removable wedge or key fitted between the divided ends of said ring, substantially as described.

In witness whereof I have hereunto signed my name in the presence of two subscribing witnesses.

MANASSAH GLEDHILL.
